UNITED STATES PATENT OFFICE.

OSCAR OTTESEN, OF TACOMA, WASHINGTON.

GAGE-GLASS FOR STEAM-BOILERS.

No. 925,784.

Specification of Letters Patent.

Patented June 22, 1909.

Application filed November 30, 1908. Serial No. 465,280.

To all whom it may concern:

Be it known that I, OSCAR OTTESEN, a subject of the King of Denmark, residing at Tacoma, in the county of Pierce and State of Washington, have invented certain new and useful Improvements in Gage-Glasses for Steam - Boilers, of which the following is a specification.

This invention relates to gage-glasses for steam boilers, which are used to indicate the stage of water and steam in the boiler.

The invention has for its object to provide a multiple gage-glass of simple and improved construction whereby, in the event of breakage of or injury to one of the glass tubes constituting the units of the device, the flow of water and steam may be directed into another tube, thus enabling the water stage to be continuously observed without stopping for repairs and enabling repairs to be postponed to a future convenient time.

Further objects of the invention are to simplify and improve the construction and operation of this class of devices.

With these and other ends in view which will readily appear as the nature of the invention is better understood, the same consists in the improved construction and novel arrangement and combination of parts which will be hereinafter fully described and particularly pointed out in the claims.

In the accompanying drawings has been illustrated a simple and preferred form of the invention; it being, however, understood that no limitation is necessarily made to the precise structural details therein exhibited, but that changes, alterations and modifications within the scope of the invention may be resorted to when desired.

In the drawings—Figure 1 is a front elevation showing the improved gage glass in position for operation. Fig. 2 is a side elevation of the same. Fig. 3 is a vertical sectional view taken on the plane indicated by the line 3—3 in Fig. 1. Fig. 4 is a vertical transverse sectional view taken on the plane indicated by the line 4—4 in Fig. 2. Fig. 5 is a horizontal sectional view taken on the plane indicated by the line 5—5 in Fig. 1. Fig. 6 is a perspective view of the regulating valve. Fig. 7 is a perspective detail view of the try-cock.

Corresponding parts in the several figures are denoted by like characters of reference.

The frame of the improved gage is composed of casings 5 and 6, having tubular

extensions 7, which are exteriorly screw-threaded, as shown at 8, to enable them to be inserted into correspondingly threaded apertures in the head or side-wall of a steam boiler 9, with which the device is to be connected. The casings 5 and 6 are connected by means of side pieces 10, and they are separated from each other by spacing members 11, the ends of which are fitted in grooves 12, in proximate faces of the casings. The latter are provided with sockets 13, 13^a and 13^b for the reception of the ends of the gage glasses 14, 14^a and 14^b, of which any desired number may be used; in the drawings hereto annexed, three such glasses have been shown.

The casings 5 and 6 are provided with vertically alined bores 15 forming seats for the regulating valve V, the valve seats 15 communicating at one side with the bores 16 of the tubular extensions 7, of the casings 5 and 6; said casings are provided with divergent channels 17, 17^a and 17^b connecting the opposite sides of the valve seats 15 with the sockets 13, 13^a and 13^b, respectively.

The sockets formed in the upper casing 5, for the reception of the upper ends of the gage glasses extend completely through said casing, the upper ends of the sockets being closed by means of screw-threaded plugs 18. The lower casing 6 has a downward extension 19, which is provided with a transverse bore 20 constituting a seat for the try-cock 21; the lower side of said bore or seat communicating with a downward extending discharge aperture 22, while the upper side of the bore or seat communicates through a plurality of divergent channels 23, 23^a and 23^b with the sockets wherein are seated the lower ends of the gage-glass. The try-cock 21, has a port or passage 24, which is so constructed that any one of the gage glasses may be placed in communication with the discharge aperture 22, or communication between said discharge aperture and each of the gage-glasses may be completely cut off. The regulating valve V has two heads 25 engaging the seats 15 in the casings 5 and 6, respectively; said heads being provided with ports or passages whereby the tubular extensions of said casings leading to the boiler may be simultaneously placed in communication with the upper and lower ends of any one of the gage glasses, or communication may be cut off when desired; for convenience in construction, the stem 26 of the regulating valve has been shown as being

formed in two pieces, assembled by a screw or fastening member 27; the valve stem is provided with a handle 28 whereby it may be conveniently manipulated, the try-cock 21 5 is likewise provided with a handle 29. The handle 28 is preferably provided adjacent to its outer end with an aperture 31, for the convenient attachment of an operating member, such as a cord, chain or the like, which 10 may be guided to a slightly distant point where it may be grasped by the operator who will thus be enabled to manipulate the valve handle 28 without danger of his hand being scalded by steam escaping through 15 a broken gage-glass.

From the foregoing description taken in connection with the drawings hereto annexed, the operation and advantages of this 20 invention will be readily understood by those skilled in the art to which it appertains. Normally the regulating valve is adjusted to place the steam and water space of the boiler in communication with one of the gage-glasses, while the try-cock is normally 25 positioned to cut off communication between the gage-glasses and the discharge aperture 22. In case of injury to or stoppage or breakage of the gage-glass which is temporarily in use, a slight turning of the regulating valve will deflect the flow of water 30 and steam into another glass, the broken or injured glass being cut off from communication with the boiler. This operation may be performed in a moment's time, and without 35 the least inconvenience or loss of time. By proper adjustment of the try-cock the gage-glasses may be blown out whenever desired.

This invention, as will be seen, is extremely simple in construction and operation, and by its use much annoyance and loss of time may be avoided.

Having thus described the invention, what is claimed is:

45 1. A gage for steam boilers, comprising a plurality of gage glasses; casings having sockets forming seats for the upper and lower ends of said glasses, vertically aligned bores forming valve seats, and tubular extensions connecting the valve seats with the

55 sockets wherein the gage glasses are seated; and a regulating valve having heads engaging the seats of the casings and provided with ports whereby communication may be established between the boiler and any one of the gage glasses.

2. A gage for steam boilers comprising casings having sockets, a plurality of gage-glasses seated in the sockets, side pieces connecting the casings, and spacing members 60 interposed between the casings and engaging grooves in the proximate faces of said casings.

3. A gage for steam boilers, comprising upper and lower casings having sockets, side 65 pieces connecting the casings, spacing members separating the casings, and a plurality of gage glasses seated in the sockets of the casings; and a regulating valve having heads seated in the casings, said valve being provided with a separable stem and means for connecting the parts of said stem.

4. In a device of the class described, an upper and a lower casing having sockets, a plurality of gage glasses seated in said sockets, plugs forming closures for the upper 75 ends of the sockets in the upper casing, a downward extension upon the lower casing having a valved discharge aperture and divergent channels connecting said aperture 80 with the sockets wherein the lower ends of the gage glasses are seated, said casings being provided with vertically aligned valve seats, with tubular extensions communicating with the valve seats at one side of the 85 latter, and with divergent channels connecting the opposite sides of the valve seats with the sockets, wherein the gage-glasses are seated; and a valve having heads engaging the seats in the casings and provided with ports through which communication may be 90 established between the tubular extensions leading to the boiler and the divergent channels leading to any one of the gage-glasses.

In testimony whereof I affix my signature 95 in presence of two witnesses.

OSCAR OTTESEN.
